(57) **CLAIM**

The ornamental design for a water treatment device, as shown and described.

DESCRIPTION

FIG. 1 is a perspective view of a water treatment device, partially from the front side of the water treatment device and partially from the bottom of the water treatment device; FIG. 2 is a front side view of the water treatment device of FIG. 1;

FIG. 3 is a bottom view of the water treatment device of FIG. 1;

FIG. 4 is a top side view of the water treatment device of FIG. 1,

FIG. 5 is a right side view of the water treatment device of FIG. 1;

FIG. 6 is a left side view of the water treatment device of FIG. 1; and,

FIG. 7 is a back side view of the water treatment device of FIG. 1.

The broken line showing of a water treatment device is for illustrating portions of the article and forms no part of the claimed design.

1 Claim, 7 Drawing Sheets
